US0D1080123S

(12) **United States Design Patent** (10) Patent No.: **US D1,080,123 S**
 Pedersen et al. (45) Date of Patent: ** Jun. 17, 2025

(54) **SHOPPING CART**

(71) Applicant: **TARGET BRANDS, INC.**, Minneapolis, MN (US)

(72) Inventors: **Sara L. Pedersen**, Minneapolis, MN (US); **Alex K. Poniatowski**, New Hope, MN (US); **Hermann Eichele**, Leipheim (DE); **Stefan Remmehle**, Offingen (DE); **Dieter Stöckle**, Landensberg (DE); **Thomas Gasche**, Leipheim (DE); **Peter Irlbacher**, Schwarzenfeld (DE); **Johann Daminger**, Neu-Ulm (DE); **William Kiser**, Lincolnton, NC (US)

(73) Assignee: **TARGET BRANDS, INC.**, Minneapolis, MN (US)

(**) Term: **15 Years**

(21) Appl. No.: **29/857,743**

(22) Filed: **Oct. 25, 2022**

(51) LOC (15) Cl. **12-02**

(52) U.S. Cl.

USPC **D34/17**

(57) **CLAIM**

The ornamental design for a shopping cart as shown and described.

DESCRIPTION

FIG. 1 is a top, rear, perspective view of the shopping cart showing a first embodiment of our new design;

FIG. 2 is a front view thereof;

FIG. 3 is a rear view thereof;

FIG. 4 is a right side view thereof;

FIG. 5 is a top view thereof;

FIG. 6 is a bottom view thereof; and,

FIG. 7 is a left side view thereof.

The broken lines in the drawings depict portions of the shopping cart that form no part of the claimed design.

1 Claim, 7 Drawing Sheets
